UNITED STATES PATENT OFFICE.

HAROLD I. STAGE, OF SAN FRANCISCO, CALIFORNIA, ASSIGNOR TO INGERSOLL-RAND COMPANY, OF JERSEY CITY, NEW JERSEY, A CORPORATION OF NEW JERSEY.

SHOVELING AND LOADING MACHINE.

Application filed September 27, 1923. Serial No. 665,041.

To all whom it may concern:

Be it known that I, HAROLD I. STAGE, a citizen of the United States, and a resident of San Francisco, county of San Francisco, 5 State of California, have invented a certain Shoveling and Loading Machine, of which the following is a specification, accompanied by drawings:

This invention relates to shoveling and 10 loading machine for shoveling and loading ore, coal and other broken materials into a suitable car.

The object of the invention is to enable a car or cars running on rails to remain in a 15 given position either on the surface or in a mine, but permit the car or cars to be loaded by a shoveling and loading machine in the form of a unit transportable under its own power and capable of traveling in any direction 20 and carrying the material in a hopper from distant points to the car or cars.

Another object of the invention is to secure suitable means in the form of a conveying element into which material is 25 dumped and from thence conveyed into the cars.

The invention is shown in one of its preferred forms in the accompanying drawings, in which—

30 Figure 1 is a side elevation of a complete unit comprising a conveyor element and a movable and transportable shoveling and loading element.

Figure 2 is an enlarged side elevation of 35 the shoveling and loading element.

Figure 3 is a longitudinal sectional elevation of the shoveling and loading element shown in Figure 2.

Figure 4 is a top plan view partly broken 40 away of the shoveling and loading element shown in Figure 3,

Figure 5 is a side elevation partly in longitudinal section of the conveying element.

Figure 6 is a top plan view partly broken 45 away of the conveying element.

Figure 7 is a side elevation of a modified form of the shoveling and loading unit.

Figure 8 is a longitudinal sectional elevation 50 of the modified form of the shoveling and loading unit shown in Figure 7, and

Figure 9, is a top plan view of Figure 8.

Referring to the drawings, a portion of a hopper car A to be loaded, is shown adapted to travel on the rails B and a shoveling and 55 loading unit C capable of being driven upon

the ground or over the floor of the mine under its own power, shovels and loads the material into the hopper D of a conveying element E adapted to be located intermediate the point of delivery of the shoveling and loading unit, and the hopper car to be loaded.

The conveying element may be of any suitable form, preferably comprising a frame, which may be mounted either on 65 wheels or the skids F, so that it may be conveniently transported from place to place or along the rails B. Uprights G support a conveyor frame H carrying the upper and lower sprocket shafts J and K and the 70 sprockets L and O, having conveying chains P, carrying the suitable flights or buckets as desired, for conveying material from the hopper D to the hopper car A. Suitable driving mechanism may be provided for the 75 conveyor, in this instance an electric motor Q being mounted on the frame and having a worm R meshing with the worm wheel S on the shaft T, supported in suitable bearings and extending outwardly beyond the 80 conveyor frame and operatively connected to a vertical shaft U having a bevel gear V, driving a countershaft X having a bevel gear W, which countershaft is also provided with a bevel gear Y meshing with a bevel gear Z on the upper sprocket shaft J by 85 means of which driving mechanism the conveyor is actuated. An electric controller a may be conveniently mounted on the upright G and current is supplied to the motor 90 through a suitable flexible cable b and connections c and d. Any other suitable operative connections may be provided between the motor and the conveyor.

The shoveling and loading element in the 95 form of a self-contained unit comprises the frame e, on which is mounted a suitable motor f, preferably an electric motor, for operating a scoop or shovel g and for furnishing power for driving the element itself. Driving wheels h having tractor surfaces are mounted on the rear axle j of the shoveling element and a single front supporting and steering wheel k is mounted on the front axle o. Front and rear sprocket shafts 100 p and q are suitably mounted on the frame of the shoveling unit and front and rear sprockets r and s are carried by said sprocket shafts over which sprocket chains t are 105 connected.

The shovel or scoop *g* is provided with arms *u* having extensions *v* bent at an angle to the main portions of the arms and these arms are pivotally mounted on a cross shaft 5 connected to opposite links of the chain *t*. The outer ends of the arm extensions *v* are connected by a shaft *x* having a roller *y*. A cross rod *z* at the back of the scoop is adapted to lie in saddles 2 mounted on the 10 chains when the shovel is in the digging position indicated in Figure 3. As the chains are driven rearwardly, the scoop or shovel picks up the material and travels upwardly with the conveyor chains and as the shovel 15 rises, the arms *u* are rocked on the pivot *w* until the roller *y* lies upon the chains. As the shovel continues upwardly, the guide roller *y* enters beneath the grooved guide 3 at the rearward end of the shoveling unit, 20 and is guided rearwardly and downwardly, thus carrying the scoop or shovel into dumping position as indicated in Figures 1 and 2, the guide roller *y* coming to rest at the stop 4 formed at the lower end of the grooved 25 guide 3 and after the material is dumped, the direction of movement of the chains is reversed and the shovel is carried downwardly to digging position, as indicated in Figure 3. With the shovel or scoop in the 30 position of Figure 3, the lip of the scoop is forced into the material by driving the whole machine forward.

Any suitable driving connections may be provided between the motor *f* and the wheel 35 *h* of the shoveling element, and between the motor and the chains. In Figures 3 and 4, combined electric and fluid pressure driving connections are shown. A pinion 5 on the motor shaft meshes with a gear 6 which 40 drives any suitable rotary pump 7 for pumping oil or other fluid from a tank 8 through the supply pipe 7^a and out through the pipe 8^a which branches and leads through suitable valves 9 and 10 to suitable rotary gear 45 motors 11 and 12. One motor 11 operates the driving wheels of the unit and the other motor 12 operates the conveyor chains. The pipe 13 connects from the pipe 8^a to the valve 9 and from thence the pipes 14 and 50 15 lead to the gear motor 11 forming the supply and outlet from said motor. Each valve 9 and 10 is a three-way valve and the pipe 16 leads from the valve 9 to a pipe 17, which connects with the tank 8 for the 55 turn of fluid.

A pipe 18 leads from the pipe 8^a on the main pump to a connection 19 from which one branch 20 connects with a three-way valve 10 and from this valve the pipes 21 and 60 22 connect with the casing of the gear pump 12. Another pipe 23 leads from the valve 10 to the pipe 16 forming a return from the pump 12. A spring actuated valve 24 is preferably inserted in the connection between the pipe 18 and the pipe 17.

One of the rotary gears 25 of the gear pump 11 is provided with a pinion 25^a meshing with a gear 26 on a counter shaft 26^a having a gear 26^b, which in turn meshes with an internal gear 27 on one of the driving 70 wheels *h*. One of the gears 28 of the gear pump 12 is operatively connected by the gear 28^a to a gear 29 on the rear sprocket shaft 75 *q* for driving the sprocket chains of the scoop.

The controlling valves 9 and 10 may be conveniently manipulated by the levers 30 and 31, on the outside of the frame of the machine. The lever 30 is connected by the chain 32 and suitable sprockets to the valve 80 9 and the lever 31 on the shaft 33 is connected directly to operate the valve 10.

In the position of the valves 9 and 10 shown in Figure 3, pressure fluid is supplied to the gear motors 11 and 12, and returns from both motors through the valve casing and back through the pipes to the tank 8. Obviously, the motive fluid for either one or both of the motors may be shut off without stopping the main pump 7, by turning 85 the valves to proper positions, so that the fluid by-passes the motors 11 and 12 and returns through the pipes 18 and 17 and the remaining connections to the tank 8. Suitable means are provided for steering the shoveling and loading unit, by turning the front wheel *h* and for this purpose the front 90 axle *a* is mounted on a turn table 34 having the worm wheel 35 meshing with the worm 95 36 on the steering shaft 37 provided with the bevel gear 38 meshing with the bevel gear 39 on the short shaft 40, carrying the handle 41. Manipulation of the crank handle 41 will turn the front wheel in the desired direction of travel.

The operation of the improved unitary shoveling and loading element or unit traveling upon its own power, is simple and efficient. The unit is particularly adapted to be used for loading cars in a coal mine, for instance, since the cars may be left stationary on the rails and the unit may be moved under its own power to any desired point within a room or heading, in order to scoop up the loose coal and carry it back to the conveying element for dumping. For this purpose the scoop or shovel is driven into the pile and then the scoop is carried part way in a rearward direction on the unit, until the scoop is substantially upright. The chains are then stopped and the unit is driven under its own power backwardly or forwardly, as desired, and backed into proximity to the hopper D of the conveying element at which time the dumping takes place. 110 The shoveling unit is then driven to another part or to the same part of the room, and another load is carried back to the conveying element.

A modification of the shoveling and load- 115 120 125 130

ing element is shown in Figures 7, 8 and 9, which is mechanically driven by chain and sprocket connections between the electric motor *f*, and the rear wheels and the chain sprockets, otherwise the construction of the unit is the same.

In the modification, the motor shaft is provided with a worm 43 meshing with a worm gear 43 on the shaft 44. A counter-shaft 45 above the shaft 44 is operatively connected to drive the sprockets *s* on the shaft *g* for operating the chains and scoop. The shaft 44 is operatively connected to drive the traction shaft *j* and operate the traction wheels *h*. The lower driving shaft 44 is provided with a sprocket 46 and a chain 47 connects said sprocket with the sprocket 48 on the shaft *g*. Another sprocket 49 on the upper shaft 45 is connected by the chain 50 with a sprocket 51 also on the shaft *g*. The upper shaft 45 has a gear 52 meshing with a gear (not shown), on the lower shaft 44. The smaller gear is loose on the shaft 44 and a clutch member 53 rotatable 25 with the shaft 44 but slidably thereon, is adapted to engage the smaller gear referred to. The sliding clutch is duplex and has a clutch member 54 adapted to engage the sprocket wheel 46 which is loose on the shaft 44. An arm 55 has a lever 56 pivoted thereto, extending to the outside of the frame of the machine and a hand lever 57 pivoted to the frame at 58, is connected to said lever 56 so that the duplex clutch having the members 53 and 54, may be moved longitudinally on the shaft 44 and connect the shaft to either one of the gears for driving the chains 47 and 50, as desired. In neutral position, neither one of the chains is driven.

The shaft 44 is also provided with a sprocket 59 connected by a chain 60 to a sprocket 61 on the traction shaft *j*. A pinion 62 loose on the shaft 44 meshes with the gear 63 on the stud 64 carrying a sprocket 65 connected by a chain 66 to a sprocket 67 on the traction shaft *j*. A duplex clutch having members 68 and 69 is slidably on the shaft 44 but rotatable therewith, and is adapted to connect either the sprocket 59 or the pinion 62 to rotate with the shaft, and thus drive the machine forwardly or backwardly. An arm 70 is connected to an

operating lever 71 extending to the outside of the machine and adapted to be operated by a lever 72 pivoted at 73 to the frame of the machine for manipulating the clutch member.

I claim:

1. A power driven self propelled shoveling and loading machine adapted to shovel material and carry it to the point at which the material is to be discharged, comprising a frame having front and rear axles, rear traction wheels on the rear axle, a front supporting and steering wheel on the front axle, a motor on the frame, operative connections between the motor and the traction wheels, front and rear sprocket shafts on the frame having sprockets, endless chain elevating mechanism connected to operate on said sprockets, operative connections between the motor and the said rear sprocket shaft for driving said shaft in either direction, and a scoop carried by said endless chain elevating mechanism, whereby the scoop is caused to travel back and forth from shoveling to dumping position.

2. A power driven self propelled shoveling and loading machine adapted to shovel material and carry it to the point at which the material is to be discharged, comprising a frame having front and rear axles, rear traction wheels on the rear axle, a front supporting and steering wheel on the front axle, a motor on the frame, operative connections between the motor and the traction wheels, front and rear sprocket shafts on the frame having sprockets, endless chain elevating mechanism connected to operate on said sprockets, operative connections between the motor and the said rear sprocket shaft for driving said shaft in either direction, and a scoop carried by said endless chain elevating mechanism, whereby the scoop is caused to travel back and forth from shoveling to dumping position, and controlling devices for independently controlling the application of power to the traction wheels and to the said elevating mechanism.

In testimony whereof I have signed this specification.

HAROLD I. STAGE.
